EXTENSION TABLE

Charles J. Miller, Chicago, Ill.

Application October 31, 1934, Serial No. 750,781

4 Claims. (Cl. 311—48)

This invention relates to extension tables which are adapted to be enlarged by the insertion of an extension or filler leaf between two movable parts of the table top; and the primary object 5 of the invention is to provide a convenient means to receive and hold the extension or filler leaf upon the frame and beneath the table top for storage while said leaf is not in use.

Another object of the invention is to provide 10 means for holding the leaf securely in storage position on the frame and beneath the top of the table so that it will not rattle or become displaced in transporting the table or in moving the table about in use.

15 And a further object is to store the extension or filler leaf compactly on the frame and beneath the table top so that it will not move about in the ordinary use of the table and so that it can be easily removed from storage position when required for use.

20 In the accompanying drawing I have illustrated the invention in one type of table for which it is adapted and referring thereto.

Fig. 1 is a top plan view of the table showing 25 the filler leaf arranged to form part of the table top;

Fig. 2 is a transverse sectional view taken at the position of the line 2—2 on Fig. 1 but showing the filler leaf in storage position;

30 Fig. 3 is a sectional view on the line 3—3 of Fig. 2;

Fig. 4 is a detail sectional view; and

Fig. 5 is a view similar to Fig. 2 with a filler leaf having a double fold in storage position.

35 Referring to the drawing, 6 designates generally the frame of the table mounted on legs 7 and supporting a top comprising the sections 8, 8' which are adapted to be guided in any suitable manner in movement toward and from each other 40 upon the frame. It will not be necessary to describe the devices which guide and control the movement of the parts of the table top because they form no part of this invention and may be changed as desired without affecting this invention.

45 The frame comprises two cross bars 9 and the extension or filler leaf 10 is adapted to be supported upon these cross bars between the side rails 11, 11' of the frame. The filler leaf 10 has an end section 10' which is hinged to the body 50 of the leaf to fold thereunder as shown in Fig. 2. The hinge 12 is fastened to the underside of the body and the fold section 10' of the filler leaf at the adjacent edges thereof so that the section 55 will fold under the body of the filler leaf with the

hinged edges of the body and the section flush to abut flatly against the rail 11' when the filler leaf is in storage position upon the cross bars 9. To cause the filler leaf to make this abutting engagement with the rail 11' when it is inserted in storage position and to retain it in abutting engagement, I provide blocks 13 which are secured to the rail 11 upon the adjacent ends of the cross bars 9. These blocks have inclined faces 14 upon which rests an end of the filler leaf in storage position and the tendency is for the filler leaf to slide down the inclines, the underfold of the leaf sliding on the cross bars 9, until the body and underfold abut the rail 11. The filler leaf is thus held snugly in storage position by reason of the fact that the tendency of the leaf to slide down the inclines 14 holds it in abutting engagement with the rail 11. To hold the filler leaf rigidly in storage position for shipment, or at other times, a pad 15 may be secured to the under- 5 side of one of the sections 8 or 8' to engage the filler leaf in storage position and press it down the inclines 14 which will have the effect of pressing the leaf tightly against the rail 11' and holding it in that position without displacement or rat- 10 tling.

15 The cross bars 9, 9 are located in a position on the frame below the filler leaf when it is in storage position and the two parts 8, 8' of the table top are adapted to be opened slightly more 20 than the width of the filler leaf to permit insertion or removal of the filler leaf from the table top, after which the parts 8, 8' are pushed into contact with the filler leaf or with each other. It is desirable to provide simple means for guiding 25 the filler leaf into storage position and for centering it in storage position between the parts 8, 8' when opened so that the operator may easily grasp the end edge of the filler leaf in inserting or removing the filler in or from storage position. For 30 this purpose I provide each block 13 with a guide 16 at the outer edge of its incline, and these guides center the filler leaf in storage position as the edge of the leaf slides down the inclines 14 and also prevent the filler leaf from becoming dis- 35 placed from storage position or rattling therein. In other words, the guides 16 engage the corners of the filler leaf as it slides down the inclines and center the leaf in storage position upon the cross bars 9 and flatly abutting the rail 11', and they 40 hold the filler leaf in this position against displacement. Furthermore, by thus centering the leaf in its storage position the operator may easily 45 insert his fingers or his hands in the opening between the parts 8, 8', when they are separated, to 50 55

grasp the end of the filler leaf for removing it from storage position, and likewise when returning the filler leaf to storage position.

- Instead of the single fold filler leaf heretofore described, I may provide a filler leaf 17 with two underfolds 18, 18' as shown in Fig. 5, in which case blocks 13' having the inclines would be correspondingly longer than the blocks 13 for the single underfold filler leaf.
- 10 I do not limit the invention to the particular embodiment herein shown and described because it may be used in other tables for which it is or may be adapted and I reserve the right to make all such changes as may be necessary or desirable for embodying the invention in other tables, or for other purposes, within the scope of the following claims:

I claim:

1. An extension table comprising a top, a frame, a folding filler leaf adapted to be arranged in storage position upon the frame and beneath the top, and inclined means on the frame engaging one end of the filler leaf in storage position whereby the force of gravity causes said leaf to ride down the incline until the opposite end of said leaf engages the frame and wedges the leaf between the inclined means and the frame.
2. An extension table comprising a top, a frame

having a side rail and cross bars, blocks on the cross bars having inclined faces, and a folding filler leaf adapted to be arranged in storage position upon the cross bars and beneath the top with one end engaging the inclined faces on said blocks and the folded end abutting said rail.

5

3. An extension table comprising a top, a frame, a removable folding filler leaf adapted to be arranged in storage position upon the frame and beneath the top, inclined means on the frame engaging one end of the filler leaf in storage position whereby the force of gravity causes said leaf to ride down the incline until the opposite end of said leaf engages the frame and wedges the leaf between the inclined means and the frame, and means on the frame for centering and retaining the filler leaf in storage position.

10

4. An extension table comprising a top, a frame having a side rail and cross bars, a folding filler leaf adapted to be arranged in storage position upon the cross bars and beneath the top, blocks on the cross bars having inclined faces to be engaged by one end of the filler leaf to cause the opposite end of the leaf to abut said rail, and guides on said blocks to center and retain the filler leaf in storage position.
